UNITED STATES PATENT OFFICE

161,154

PORTABLE ELECTRIC FOUNTAIN

Robert L. R. Bartholomew, Chester Springs, Pa.

Application May 2, 1950, Serial No. 9,635

Term of patent 14 years

(Cl. D91—4)

To all whom it may concern:

Be it known that I, Robert L. R. Bartholomew, a citizen of the United States, residing in Chester Springs, county of Chester, State of Pennsylvania, have invented a new, original, and ornamental Design for a Portable Electric Fountain, of which the following is a specification, reference being had to the accompanying drawing, forming a part thereof.

In the said drawing, Fig. 1 is a view in perspective of a portable electric fountain, showing my new design, and

Fig. 2 is a side elevation thereof in which one of the parts is broken away in section, an electric conduit for supplying power to the fountain being indicated by broken lines in both figures.

I claim:

The ornamental design for a portable electric fountain, substantially as shown and described.

ROBERT L. R. BARTHOLOMEW.
